UNITED STATES PATENT OFFICE.

JOSEPH WHITE, OF PISCATAWAY TOWNSHIP, NEW JERSEY, ASSIGNOR TO HALL PRINTING PRESS COMPANY, OF DUNELLEN, NEW JERSEY, A CORPORATION OF NEW JERSEY.

PLATE-CLAMP.

1,345,300.

Specification of Letters Patent. Patented June 29, 1920.

Application filed September 24, 1919. Serial No. 325,944.

To all whom it may concern:

Be it known that I, JOSEPH WHITE, a citizen of the United States, residing at Piscataway township, State of New Jersey, (Post-office address, Boundbrook, New Jersey,) have invented certain new and useful Improvements in Plate-Clamps; and I do declare the following to be a full, true, and exact description of said invention, such as will enable others skilled in the art to which it appertains to make and use the same.

This invention relates to clamps for holding flexible plates or sheets on a supporting bed, and particularly clamps for positioning and holding flexible planographic printing plates on the beds of printing presses.

In order to adjust such a plate in a printing press so as to bring it into proper printing relation, particularly with previously printed forms, it is desirable not only to be able to adjust the sheet as a whole both lengthwise and crosswise of the bed, but it is also desirable at times to stretch the sheet laterally. It is to accomplish this purpose that my present invention is particularly adapted.

With these and other objects in view, my invention consists of certain novel features of construction, combination and arrangement of parts, as will be more fully described and pointed out in the appended claims.

In the drawings, Figure 1 represents a plan view of a printing press cylinder, which I have adopted for purposes of illustration, in which an illustrative form of clamp is shown holding the printing plate in position; Fig. 2 is a plan, Fig. 3 a front elevation and Fig. 4 a side elevation, partly in section, of an enlarged view of one of the clamps in my preferred form, as arranged to carry out my present invention.

The corresponding parts are referred to, both in the specification and in the drawings, by similar reference characters.

My present invention is illustrated in connection with a printing cylinder 10 of the usual construction, mounted in bearings in the frames 11, the cylinder having a bed 12 extending partially around the cylinder. The printing plate 13 is wrapped around the bed 12 and held in place by a series of

clamps along each edge of the plate. The 55 form of clamp which I have adopted for purposes of illustration has a body portion 14 with a fixed jaw 15 and a movable jaw 16 pivoted at 17 and controlled by the screws 18, so that the edge of the plate may be 60 clamped between the jaws 15 and 16. Each clamp is separately pivoted in bearings in the end of the cylinder or in the block 20, the latter being held to the cylinder by the bolt 21. A screw 19 is threaded into the 65 body member 14 and exerts a pressure against the edge of the bed 12, so that when the screw 19 is turned, the clamp is moved away from the bed to stretch the plate. The arrangement so far described is the 70 usual one and no further detailed description will be necessary for an understanding of it.

If, for any reason, it is desired to stretch the plate laterally along one or both of its 75 edges, so as to bring the design into proper register with previously printed forms, the arrangement which I provide will permit this to be accomplished. To this end, I mount the clamps in their respective bearings so that some end motion of the clamp is permitted, and in the form illustrated, the clamp is moved endwise by means of a screw 23 threaded into an ear 22 forming part of the bearing 20, the screw 23 pressing against 80 one end of the clamp. While, for some purposes, it might be desirable to provide means for moving each of the clamps along an edge, I have found it to be sufficient to provide moving means for the end clamps 85 only, as illustrated in Fig. 1. The screws 23 are arranged so that each end clamp may be moved away from the center of the plate, so that the same may be stretched to the amount desired.

Since the endwise motion to the clamp will be given while the sheet is under tension, or, in other words, while the screw 19 is pressing with a heavy pressure against the front of the bed 12, I have found it desirable to provide some means by which the clamp can be moved endwise while the screw 19 is exerting its pressure. To this end, I provide an anti-friction bearing between the end of the screw 19 and the front of the 100 bed, my preferred form of bearing, as illustrated, comprising a plate 24 against which the end of the screw 19 rests, the plate 24

being held in place by screws 25—25 passing through slots in the plate 24. The plate 24 is held yieldingly in its normal position by a spring 26 positioned between the plate and a puppet 27 attached to the bed 12. In a suitable opening in the plate 24 are placed anti-friction devices, which, in the form illustrated, comprise a pair of rollers 28 the ends of which are held in members 31 forming cages for the rollers, these cages being held in normal position by a spring 29 between the members 31 and puppets 30 attached to the plate 24.

With the arrangement shown, it will be obvious that the clamp may be moved bodily endwise even when under very great stretching pressure from the screw 19; because this pressure is carried by the rollers 28, which will turn as the plate is moved sidewise.

While I have illustrated my invention in connection with a cylinder, it will be obvious that it may be used on any form of printing bed and that the particular embodiment of my invention may be varied within wide limits without departing from its spirit.

What I claim and desire to secure by Letters Patent of the United States is:

1. A sheet-supporting bed, devices for holding a flexible sheet thereon, comprising a plurality of separate clamps positioned along one of the edges of the sheet and adapted to grip said edge, and positively actuated means whereby one of said clamps may be moved longitudinally of said edge and independently of the remaining clamps, and while the clamp being moved is under strain to hold the sheet on said bed.

2. A sheet-supporting bed, devices for holding a flexible sheet thereon, comprising a plurality of separate clamps positioned along opposite edges of the sheet and adapted to grip said edges, and positively actuated means whereby one of said clamps may be moved longitudinally of the edge with which it engages and independently of the remaining clamps, and while the clamp being moved is under strain to hold the sheet on said bed.

3. A sheet-supporting bed, devices for holding a flexible sheet thereon, comprising a plurality of separate clamps positioned along one of the edges of the sheet and adapted to grip said edge, and positively actuated means whereby at least two of said clamps may be moved in opposite directions longitudinally of said edge independently of the remaining clamps, and while the clamps being moved are under strain to hold the sheet on said bed.

4. A sheet-supporting bed, devices for holding a flexible sheet thereon, comprising a plurality of separate clamps positioned along opposite edges of the sheet and adapted to grip said edges, and positively actuated

means whereby at least two of said clamps on each edge may be moved in opposite directions longitudinally of said edges independently of the remaining clamps, and while the clamps being moved are under strain to hold the sheet on said bed.

5. A sheet supporting bed, devices for holding a flexible sheet thereon, comprising a clamp adapted to grip the edge of the sheet, pressure devices adapted to exert pressure against the bed to move the clamp to stretch the sheet on the bed, and positively actuated means whereby one of said clamps may be moved longitudinally of said edge independently of the remaining clamps and while the clamp being moved is under strain to hold the sheet on said bed.

6. A sheet supporting bed, devices for holding a flexible sheet thereon, comprising a clamp adapted to grip the edge of the sheet, pressure devices adapted to exert pressure against the bed to move the clamp to stretch the sheet on the bed, anti-friction devices between the bed and said pressure devices, and means whereby the clamp may be moved along the edge of the bed while said pressure devices are holding the sheet stretched.

7. A sheet supporting bed, devices for holding a flexible sheet thereon, comprising a clamp adapted to grip the edge of the sheet, pressure devices adapted to exert pressure against the bed to move the clamp to stretch the sheet on the bed, anti-friction devices comprising a movable plate and rollers between the bed and said pressure devices, and means whereby the clamp may be moved along the edge of the bed while said pressure devices are holding the sheet stretched.

8. A sheet supporting bed, devices for holding a flexible sheet thereon, comprising a clamp adapted to grip the edge of the sheet, a screw adapted to exert pressure against the edge of the bed to move the clamp to stretch the sheet on the bed, a member contacting with the end of the screw and movable longitudinally of the edge of the plate, rollers between said plate and the edge of the bed, and means whereby the clamp may be moved along the edge of the bed while said screw is holding the sheet stretched.

9. A sheet supporting bed, devices for holding a flexible sheet thereon, comprising a clamp adapted to grip the edge of the sheet, a screw adapted to exert pressure against the edge of the bed to move the clamp to stretch the sheet on the bed, a plate mounted on the edge of the bed and movable longitudinally thereof and adapted to contact with the end of the screw, anti-friction bearings between said plate and said bed, and means whereby the clamp may be

moved along the edge of the bed while said screw is pressing against said plate to hold the sheet stretched.

10. A sheet supporting bed, devices for holding a flexible sheet thereon, comprising a plurality of separate clamps positioned along one of the edges of the sheet and adapted to grip said edge, and means to move said clamps to stretch the edge of the plate longitudinally thereof and to hold the plate in its stretched position.

11. A sheet supporting bed, devices for holding a flexible sheet thereon, comprising a plurality of separate clamps positioned along opposite edges of the sheet and adapted to grip said edges, and means to move said clamps to stretch the edges of the plate longitudinally thereof and to hold the plate in its stretched position.

20 12. A sheet supporting bed, devices for holding a flexible sheet thereon, comprising a plurality of separate clamps positioned along one of the edges of the sheet and adapted to grip said edge, and positively actuated means to move one of said clamps longitudinally of said edge independently of the remaining clamps and to hold the clamp in adjusted position.

13. A sheet supporting bed, devices for holding a flexible sheet thereon, comprising 30 a plurality of separate clamps positioned along opposite edges of the sheet and adapted to grip said edges, and positively actuated means to move one of said clamps on each edge longitudinally of said edge independently of the remaining clamps on that edge and to hold the clamp in adjusted position.

14. A sheet supporting bed, devices for holding a flexible sheet thereon, comprising 40 a plurality of separate clamps positioned along one of the edges of the sheet and adapted to grip said edge, and positively actuated means to move at least two of said clamps in opposite directions longitudinally of said edge and to hold the clamps in ad- 45 justed position.

15. A sheet supporting bed, devices for holding a flexible sheet thereon, comprising a plurality of separate clamps positioned 50 along opposite edges of the sheet and adapted to grip said edges, and positively actuated means to move at least two of said clamps on each edge in opposite directions longitudinally of said edge and to hold the clamps in adjusted position.

JOSEPH WHITE.
